No. 834,269.

PATENTED OCT. 30, 1906.

E. CUNNIFF.

THREAD PARTING MECHANISM FOR LOOMS.

APPLICATION FILED MAY 21, 1906.

UNITED STATES PATENT OFFICE.

EDWARD CUNNIF, OF NEW BEDFORD, MASSACHUSETTS, ASSIGNOR TO
DRAPER COMPANY, OF HOPEDALE, MASSACHUSETTS, A CORPORATION
OF MAINE.

THREAD-PARTING MECHANISM FOR LOOMS.

No. 834,269.

Specification of Letters Patent.

Patented Oct. 30, 1906.

Application filed May 21, 1906. Serial No. 317,888.

To all whom it may concern:

Be it known that I, EDWARD CUNNIF, a citizen of the United States, and a resident of New Bedford, county of Bristol, State of Massachusetts, have invented an Improvement in Thread-Parting Mechanism for Looms, of which the following description, in connection with the accompanying drawings, is a specification, like characters on the drawings representing like parts.

This invention relates more especially to automatic filling-replenishing looms of the so-called "feeler" type, wherein the running filling is replenished prior to complete exhaustion, and it has particular adaptation to double-fork looms.

In United States patent to Draper, No. 683,423, dated September 24, 1901, mechanism is provided to part the thread of the filling-supply to be abandoned, such thread extending from the cloth to the shuttle, and to catch or clamp the severed thread and carry it forward, so that it will be brought into the range of a temple thread-cutter to be severed thereby adjacent the cloth.

When the loom has a filling-fork at the side adjacent the replenishing mechanism, such fork is located between the temple thread-cutter and the separate parting and clamping device above referred to, the latter being in practice mounted on a shuttle-feeler. As the latter returns to normal inoperative position, with the parted thread held by the clamp, such thread is drawn across or against the filling-fork, and sometimes this causes the thread to be drawn out rearwardly from the clamp before it can be severed by the temple thread-cutter. When this occurs, the piece of thread is apt to be carried back into the cloth and makes an imperfection therein. This faulty action is liable to occur in any double-fork loom of the character hereinbefore referred to, and as such looms are very largely in use I have shown my invention as applied to a loom of that type.

My invention has for its object the production of means which prevent the parted piece of filling from being drawn out of the clamp, and said means also serve to retain the thread in position to be clamped and parted.

The novel features of my invention will be fully described in the subjoined specification

and particularly pointed out in the following claims.

Figure 1 is a top plan view of a sufficient portion of a double-fork automatic filling-replenishing loom having a temple thread-cutter and clamping and parting means with my invention applied thereto. Fig. 2 is a side elevation of the clamping and parting means in normal or retracted position with the clamp closed. Fig. 3 is an inner side view, enlarged, of the thread-parter and thread-clamp in position to act upon the thread and showing the novel feature of my invention. Fig. 4 is a vertical section thereof on the line 4-4, Fig. 3, looking toward the left.

The parter and clamp are so constructed and arranged that they will be in position to act upon the thread when the shuttle is boxed and are mounted on the shuttle-feeler, as in the patent referred to; but I have omitted the thread-catcher shown therein, and, as will appear, the greater part of the mechanism herein shown is the same as in the Draper patent aforesaid.

Referring to Fig. 1, the lay A, filling-feeder F, the transferer f', the controlling rock-shaft d', Fig. 2, turned in the direction 80 of arrow 50, Fig. 2, to effect filling-replenishment, the temple T, and temple thread-cutter e²⁰, the shuttle-feeler Y, mounted to rock on the stud o, Fig. 2, and also to move laterally thereon, the arm d¹², fast on rock-shaft 85 d' and bearing on the pin 30 on the shuttle-feeler, and the spring S² may be and are all substantially as in the patent referred to and operate as therein set forth.

The upper end of the feeler Y is notched at 92 1, Figs. 2 and 3, to receive the filling-thread 1, when the feeler is moved into operative position adjacent the mouth of the shuttle-box P², Fig. 1, and a fixed cutting-blade 2 is secured to the feeler at the lower edge or face 95 of the notch 1; such face having a transverse shoulder 3 thereon.

The movable member 4 is mounted on the screw-stud 4⁸, Fig. 3, and rests against the flat side of the feeler, this member serving as a combined clamping-jaw and cutting-blade, its lower edge coöperating with the blade 2 to part the filling-thread, and it also coöperates with the relatively fixed member 7 of the thread-clamp, said member 7 having a transverse shoulder 5 in alignment with the shoulder 3.

der 3. This fixed member 7 is held in place by the stud 4^x and by a pin 10 in the feeler, passed through a slot 9 in the member 4, the latter having a depending heel 9, a spring-washer 11 being interposed between the head of the stud 4^x and the member 7 of the thread-clamp, pressing the latter against the blade-jaw 4, and the latter is in turn held against the side of the feeler. I have thus made the thread-clamp and the thread-parter each comprise a movable and a relatively fixed member, and the two devices have the movable member 4 in common, as in Patent No. 683,423, referred to.

When the parter and clamp are in operative position, the filling-thread will enter the notch 1 of the feeler and the aligned shoulders 3 and 5 will pass behind the thread, serving to guard against the thread drawing back out of the notch before the clamping and parting action. Thereupon the member 4 is operated by engagement of the lay with the heel 6, as is usual, and the thread *t*, Fig. 4, is pressed down over the member 7 between it and the blade-jaw 4, and as the latter member reaches dotted-line position, Fig. 4, it will coöperate with the fixed cutting-blade 2 and part the thread.

Referring to Fig. 1, I have shown two filling-forks *f*^x *g*^x at opposite sides of the loom, the fork *g*^x being located between the temple *T* and the feeler *Y*, and as the feeler returns to normal position the clamped filling end *t* is drawn forward against the fork *g*^x. This tends to cause the filling to slip or draw out of the clamp rearwardly, so that it cannot be brought into range of the temple thread-cutter *c*¹⁰, but herein the shoulder 5 acts to resist such rearward pull on the thread, aiding the clamp in retaining its hold on the thread until it is positioned properly for the cutter *c*¹⁰. As the thread has been parted, the shoulder 3 at this particular time has no function; but when the thread first enters the notch 1 of the feeler both shoulders act to prevent any twist or kink in the thread, withdrawing it from the notch before it is clamped and parted.

Herein I have dispensed with the thread-catcher of the patent referred to; but the arm *E*, having a head *e*', is provided with a cam device *e*', Fig. 2, substantially as in said patent, to coöperate with a pin 12 on the blade-jaw 4 and open the latter as the feeler moves forward.

When the clamp and parter are moved bodily into operative position, the blade-jaw 4 is open and the heel 6 is in the path of a portion of the lay to be struck as the same completes its forward beat, acting through the blade-jaw 4 to clamp and part the thread *t* adjacent the shuttle.

The action on the return of the feeler to normal position has been already described.

Having fully described my invention, what

I claim as new, and desire to secure by Letters Patent, is—

1. In an automatic filling-replenishing loom, a thread-parter and a thread-clamp, to act upon the thread of the filling-supply to be abandoned, said parter and clamp having a movable member in common, means on the relatively fixed member of the clamp to retain the thread in position and prevent it from drawing out of the clamp after it has been parted, and means operating through said movable member to effect clamping and parting of the thread upon replenishment of filling.

2. In an automatic filling-replenishing loom, a thread-parter and a thread-clamp, to act upon the thread of the filling-supply to be abandoned, said parter and clamp having a movable member in common, a transverse shoulder on the relatively fixed member of the clamp to pass behind the thread and retain it in position to be acted upon, and to prevent it thereafter from drawing out of the clamp, and means operating through said movable member to effect clamping and parting of the thread upon replenishment of filling.

3. In an automatic filling-replenishing loom, a thread-parter and a thread-clamp, bodily movable upon replenishment of filling into position to act upon the thread of the filling-supply to be abandoned, the parter and clamp including a common movable member, a transverse shoulder on the relatively fixed member of the clamp to pass behind the thread and retain it in position to be acted upon, and means acting through said movable member to clamp and part the thread, the shoulder also coöoperating with the clamp to hold the thread after it has been parted.

4. In a loom provided with automatic filling-replenishing mechanism, a shuttle-feeler having a thread-receiving notch in its end, a transverse shoulder on the lower face of the notch, a fixed parting-blade adjacent the notch, a clamping-jaw mounted on the feeler, adjacent and parallel to the blade and having a transverse shoulder aligned with the shoulder on the feeler, a combined parting-blade and clamping-jaw movably mounted on the feeler between the fixed blade and jaw, the shuttle-feeler being adapted to move into operative position prior to change of filling, to thereby position the parting and clamping devices to act upon the thread of the filling-supply to be abandoned, the aligned shoulders at such time passing behind the thread and retaining it in the clamp after it has been parted, and means to act upon the movable combined blade and jaw to effect clamping and parting of the thread.

5. In an automatic filling-replenishing loom, two filling-forks, located at opposite sides of the loom, a temple thread-cutter at

the replenishing side of the loom, a thread-parter and a thread-clamp at the same side, to act upon the thread of the filling-supply to be abandoned; said parter and clamp having a movable member in common, a transverse shoulder on the relatively fixed member of the clamp to pass behind the thread, and means acting through the movable member to effect clamping and parting of the thread upon filling-replenishment, the shoulder assisting the clamp in holding the thread when parted until acted upon by the temple thread-cutter.

6. In an automatic filling-replenishing loom, a temple thread-cutter at the replenishing side of the loom, a thread-parter and a thread-clamp at the same side, to act upon the thread of the filling-supply to be abandoned,

the parter and clamp including a movable and a relatively fixed member, a transverse shoulder on the relatively fixed member of the clamp, a filling-fork between the temple thread-cutter and the clamp and parter, and means to operate the latter parts upon filling-replenishment, to clamp and part the thread, the shoulder resisting any tendency of the parted thread to draw out of the clamp if engaged by the filling-fork before being severed by the temple thread-cutter.

In testimony whereof I have signed my name to this specification in the presence of two subscribing witnesses.
